UNITED STATES PATENT OFFICE.

FRANK W. MERRICK, OF BOSTON, MASSACHUSETTS, ASSIGNEE TO POWER NUMBERING MACHINE COMPANY, OF BOSTON, MASSACHUSETTS, A CORPORATION OF MASSACHUSETTS.

MARKING OR NUMBERING MACHINE

1,172,897.

Specification of Letters Patent. Patented Feb. 22, 1916.

Application filed January 13, 1911. Serial No. 602,403.

To all whom it may concern:

Be it known that I, FRANK W. MERRICK, a citizen of the United States, residing at Boston, in the county of Suffolk, State of Massachusetts, have invented a certain new and useful Improvement in Marking or Numbering Machines, of which the following is a specification, reference being had therein to the accompanying drawings.

The invention consists in a work-support or backing for marking and numbering machines, and is of a character which adapts it more especially for use in marking or numbering successively sheets, pages, or articles which are applied thereto in piles or bundles and respectively removed after successively being marked or numbered by a movable printing-head while supported or backed up by the said work-support or backing, the remainder of the pile or bundle remaining in place until each sheet, page or article composing the same has in turn been operated upon and removed.

More particularly, the invention consists in a self-adjusting work-support or backing, the position of which is automatically controlled by the work, such position being fixed by the thickness of the pile or bundle of work.

In the preferred mode of carrying the invention into effect the work-support or backing is movably mounted, and is pressed yieldingly toward the printing-face, and has combined therewith means for intermittently locking and releasing the same. Such means operates to release the work-support or backing for the impression, permitting the automatic adjustment with relation to the printing-face to occur through contact of the printing surface with the work, and then locks the work-support or backing to retain such adjustment during the time that the printing-face is separated from the material.

An embodiment of the invention in its preferred form is shown in the drawings, in which latter,—

Figure 1 is a partly-sectional side elevation of a marking machine having the said embodiment of the invention applied thereto. Fig. 2 is a view mainly in vertical section showing the work-supporting plate of

Fig. 1, and the locking device which is combined therewith. Fig. 3 is a view in horizontal section in the plane of line 3, 3, Fig. 2, looking downward. Fig. 4 is a front elevation of the machine, with certain portions broken away.

Referring to the drawings—the invention is shown applied to a machine of the same general construction save with respect of the work-support, as the machine shown and described in United States Letters Patent granted to me May 31, 1910, No. 960,029. The drawings show the frame of the machine of the said patent comprising the base 1 and cheek-pieces 2, 3. Also, the type-head, the type-head carrier, the supporting and operating mechanism for the type-head carrier and type carriers, and the inking-devices, of the machine of the patent, the same reference characters being applied thereto as in the patent. 31 is the said type-head carrier, and 14 one of the side-pieces or cheeks of the type-head, one of the type-carriers, i. e., type-wheels, being shown at 15, Fig. 1, and 27 are the movable detents for the type-carriers, for locking them in the positions in which they have been set with the aid of the knurled head or wheel 181. 34 is the lever-like rocker by which the type-head carrier is supported and through which movement is transmitted thereto, 37 being the center-screws by which the upper end of the said carrier is connected pivotally with the front end of the said rocker, and 35 being the center-screws by which the body-portion of the rocker is mounted between the cheek-pieces 2, 3, of the machine-frame.

39 is the radius-arm which assists in controlling the path of movement of the type-head carrier and the type-head, 42 being the center-screws by which the front end of the said radius-arm is connected pivotally with the carrier, and 40 being the screws by which the rear end of the radius-arm is mounted pivotally between the cheek-pieces 2, 3.

72 is the counterbalancing spring having one end thereof engaged with the rear arm of rocker 34 and the other end thereof engaged with the rocker-portion of the radius-arm 39.

57 is the pitman or connecting-rod which joins the rear arm of the rocker 34 to the actuating crank 58 on the short shaft 59 carrying the loose spur-gear 66 meshing 5 with the pinion 65 on the power or driving shaft 62, the latter carrying the band-pulley 63 receiving the driving-band 64 through which driving-shaft 62, spur-pinion 65 and spur-gear 66 are continuously 10 driven. As in the patent aforesaid, a clutch is provided in connection with spur-gear 66 by means of which it may be made fast to the crankshaft temporarily, at the will of the operator, for the purpose of enabling 15 the machine to be actuated to print.

At 44 is the ink-pad, and at 45 the ink-pad carrier, 47 being the center-screws by which the rear end of such carrier is mounted pivotally between the cheek-pieces 2, 3, and 49 20 being the link by which the ink-pad carrier 45 is connected with the arm 31^a of the type-head carrier 31 for the purpose of causing the ink-pad carrier to be operated with timing properly coöordinated with the movements of the type-head carrier and type-head. 25

It will be understood that crank-shaft 59 normally stands at rest, with crank 58 in a depressed position, and with the type-head 30 carrier and type-head in an elevated position and stationary. It will further be understood that when the operator operates the clutch to make the spur-gear 66 temporarily fast with the crank-shaft the latter 35 is thereby caused to make one rotation, the effect of which is to depress the type-head carrier and type-head to carry the printing surfaces to printing position, and then raise the type-head carrier and type-head to their 40 original position, where they remain until the action is to be repeated. The drawings show the type-head carrier and type-head nearly, but not quite, depressed to the printing position.

45 The type-head, and the means and manner of supporting and operating it, may be as herein shown and described, and as in my Letters Patent aforesaid, or may be constructed, supported, and operated otherwise, 50 as preferred.

Referring now to the work-support,—at 5 is the work-supporting arm or rocker of the patent aforesaid, it being shown mounted pivotally at its rear end between cheek-pieces 2, 3, of the machine-frame by means 55 of center-screws 9, 9, as in the patent, 11 being the spring-actuated pin of the patent, carried by the arm or rocker 5 and resting by its lower end upon base 1 of the machine-frame to yieldingly sustain the arm or rocker 5 in its normal position, and 12, 12^a are the adjusting and lock-nuts of the spring that is employed in connection with the said pin. To the work-supporting arm or rocker 60 65 5 I apply the work-supporting plate and the

special features in connection with the latter which I will now explain.

The work-supporting plate or surface is shown at *a*. It is movably mounted upon the arm or rocker 5, being guided in its movements by means of the stem or standard *a'* extending down from it and working in the guide-socket *a²* with which the arm or rocker 5 is provided. Stem or standard *a'* fits within the said guide-socket and is capable of moving up and down therein. It is hollow, and receives within it an expanding spiral spring *b*, which latter, as will be seen, is completely housed and concealed within the stem or standard and the guide-socket. 70 The spring by its expansive power tends to support the work-supporting plate or surface *a*, and also move it toward the type-head. Provision is made for regulating the tension of the spring, by means of the collar *b'* upon which the lower end of the spring rests, and the adjusting screw *b²* for such collar, the said screw extending through a plain hole in the bottom of the guide-socket; *a²*, it being held from endwise movement by 75 collars above and below said bottom, and its threaded stem being in screw-threaded engagement with the collar.

In connection with the work-support or backing *a* I employ an intermittent lock by 80 which, at times, the work-support or backing is locked from movement under the action of the spring. This lock acts in connection with a pin *a³* which extends down from the work-support or backing at one side of the stem or standard *a'*, and works through a hole in a lug *a⁴* projecting laterally from the exterior of guide-socket *a²*. The pin fits the hole, and not only holds the work-support or backing from turning in a horizontal 100 direction, but is furnished with an enlargement or head *a³¹* at its lower end which serves by engagement with the bottom of the lug *a⁴* to limit the extent of the rise of the work-support or backing when not otherwise restrained. The lock comprises a dog, 105 constituted by a lever *c* which is entered at its engaging end within a vertical slot in the rear side of lug or block *a⁴*, and mounted therein upon a transversely-extending pivotal pin *c'*, such pin being locked in place by a clamping-screw *c²*, Figs. 1 and 3. Dog *c* has connected therewith one extremity of a contracting spiral spring *d*, which is engaged with a screw *d'* carried by the tail of the dog, the other extremity of the said 110 spring being engaged with a screw *d²* applied to the lower end of guide-socket *a²*. The dog is provided with an eccentric engaging portion, as shown in Fig. 2, which 115 when the spring *d* is permitted to actuate the dog bites against the pin *a³* and thereby locks the work-support or backing from movement under the action of the spring *b*. Provision is made for disengaging the dog 120

from the pin a^3 at the desired times in the working of the machine, to free the work-support or backing at such times to the action of spring b . In the present instance, a 5 rod e is pivotally connected at its upper end, as at e' , with an extension e^2 of radius-arm 39, projecting rearwardly beyond the center-screws 40 by which the radius-arm is mounted between the cheek-pieces 2, 3, of the machine-frame. The lower end-portion of the 10 rod e passes through a hole in the tail of dog c . Below the said tail it carries a collar e^3 which is screwed upon the screw-threaded end-portion of the rod, and is adjustable on 15 said end-portion in the direction of the length of the rod.

As the type-head carrier and type-head are actuated through the mechanism for such purpose which has been described, the 20 radius-arm is caused to swing upon its supporting center-screws 40, in consequence of its connection by the center-screws 42 with the type-head carrier. The swinging movement of the radius-arm operates to occasion 25 a movement of rod e in the direction of the length of the rod. Each time the type-head carrier and type-head move upward away from the work-support or backing, the rod e is moved in the direction to carry the collar e^3 30 away from the dog c , leaving the latter free to the influence of its spring d , and permitting the said spring to cause the eccentric portion of the dog to bite against pin a^3 , so as to lock the work-support or backing a . 35 Each time the type-head carrier and type-head move downward toward the work-support or backing, the rod e is moved in the direction to carry collar e^3 against the dog c , and move the latter so as to relieve the 40 pressure of the eccentric portion against the pin a^3 , thereby unlocking the work-support or backing.

In practice, the parts are arranged and 45 adjusted so that while the printing-surfaces of the type-carriers carried by the type-head are separated from the material upon the work-support or backing the work-support or backing is locked, and so that it continues locked until in a subsequent printing movement of the type-head carrier and type-head the said printing-surface returns to the printing plane. At substantially this moment the engagement of collar e^3 with dog c unlocks the work-support or backing, leaving it free either to be depressed by pressure 50 of such printing-surface upon the top of the material resting upon the work-support or backing, until the top of the material has been pressed down to the printing-plane, or 55 to be raised by the spring b until the top of the material and the printing-surface take proper bearing against each other. In either case the tension of the spring b produces the contact required for the printing. As the re- 60 turn movement of the type-head carrier and

type-head begins, the reverse movement of rod e and collar e^3 releases the dog c to the action of spring d , which immediately causes the dog to lock the work-support or backing in the position it has been caused to assume by 70 the pressure of the printing-surface upon the top of the material, and the dog holds the work-support or backing locked in such position until the next printing action takes place, when, as the printing-surface approaches the printing-plane another release of the work-support or backing, and automatic adjustment thereof, take place. 75

It will be obvious that the position of the work-support or backing in relation to the printing-surface is determined by the thickness of material interposed between the two. 80

The invention is useful in various connections in practice, and particularly for printing shoe-linings, pieces of leather constituting vamps or quarters of shoes, or other pieces or parts composed of sheet material which are handled in bundles. 85

I claim as my invention:

1. In a marking or numbering machine, 90 in combination, a printing head having a reciprocating printing stroke, a work-support in the line of the said printing stroke, an intermittent lock operated independently of the pressure against the work, releasing the 95 work-support as the printing surface closes upon the work, and operating while the printing head is withdrawn to retain the work-support in the position given to it by contact of the printing surface with the 100 work, and means for operating the unlocked work-support to cause the work to meet the printing surface as the printing head makes its stroke, and also to take proper bearing against the printing surface for the impression, in addition to permitting the work-support to adjust itself under pressure of the printing surface against the work until the printing head has reached the limit of the printing stroke. 110

2. In a marking or numbering machine, 115 in combination, a reciprocating printing head, and a self-adjusting work-support or backing, located in the line of the printing stroke of the printing head, controlled as to its position during printing and subsequently by the thickness of the work, and supporting the work for the impression.

3. In a marking or numbering machine, 120 in combination, a reciprocating printing head, a work-support or backing, spring-actuated to meet the type and support the work for the impression and type-actuated in the opposite direction, and an intermittent lock releasing the work-support or 125 backing for the impression and then re-locking the same.

4. In a marking or numbering machine, 130 in combination, a reciprocating printing head, a work-support or backing located in

the line of the printing stroke, actuated by yielding force to carry the work to meet the printing head and support the work for the impression, and a lock normally holding the 5 work-support or backing in fixed position and released by the printing head as the latter arrives at the printing point.

In testimony whereof I affix my signature in presence of two witnesses.

FRANK W. MERRICK.
